Mounting for Windshield Cleaners

Filed May 22, 1925

2 Sheets-Sheet 2

FIG. 4.

UNITED STATES PATENT OFFICE.

ALBERT E. DOMAN, OF ELBRIDGE, NEW YORK.

MOUNTING FOR WINDSHIELD CLEANERS.

Application filed May 22, 1925. Serial No. 32,171.

This invention relates to a mounting for motor driven wind shield cleaners in which an oscillating motion is transmitted from the motor to the wiper through the medium of speed-reducing gearing and in such manner as to apply considerable force to the operation of the wiper by the expenditure of a minimum amount of current energy.

The main object is to produce a unitary article of manufacture of this character in which all the parts may be assembled in compact relation within a comparatively small space and easily and quickly attached to the top rail of the wind shield of any closed or open car without in any way obstructing the forward vision of the driver through the wind shield.

Other objects and uses relating to specific parts of the device will be brought out in the following description.

In the drawings:

Figure 1 is a rear face view of a portion of a wind shield and my improved wiper operating mechanism mounted thereon.

Figure 2 is an enlarged horizontal sectional view taken on line 2-2, Figure 1.

Figure 3 is an enlarged horizontal sectional view through the gear case in a plane below that shown in Figure 2 or rather in a plane below the bearing for the motor shaft.

Figures 4, 5 and 6 are enlarged transverse vertical sectional views taken respectively on lines 4-4, 5-5, and 6-6, Figure 1.

Figure 7 is an enlarged front face view of the device shown in Figure 1 except that the connections between the rock shaft and wiper operating arm and also between said arm and the wiper supporting arm are shown in section.

Figure 8 is a transverse vertical sectional view taken in the plane of line 8-8, Figure 4.

As illustrated, the wiper-operating device is mounted upon the top rail as a of a wind shield A and comprises an electric motor 1 having its armature shaft 2 extended a considerable distance from one end of the armature and journaled in a tubular bearing 3 which forms a part of a gear case or housing 4 .

The gear case is substantially rectangular and is preferably comparatively shallow vertically to correspond as closely as possible

to the vertical width of the top rail a of the wind shield to which it is attached.

The side of the gear case 4 adjacent the inner face of the rail a is provided with an external threaded tubular nipple 5 of sufficient length to extend entirely through and beyond the front face of the rail a to be clamped thereto in a manner presently described.

As illustrated more clearly in Figure 4, a metal plate 6 is interposed between the rear face of the rail a and adjacent side of the gear case 4 and is provided at its upper edge with a forwardly offset flange 7 adapted to rest upon the upper edge of said rail to hold the plate against lateral rocking movement.

This plate extends downwardly across the inner face of the rail a and is provided with a vertically elongated slot 8 for receiving the tubular nipple 5 and a shallow boss 9 which projects forwardly from the front face of the gear case 4 below the tubular nipple 5 to cooperate with said nipple in holding the gear case in a horizontal position when adjusted for use.

The object of the slot 8 is to permit the plate 6 to be adjusted vertically relatively to the case 4 and its boss 9 to conform to rails of different widths or heights without effecting the position of the gear case as determined by the opening in the rail a through which the tubular nipple 5 is passed.

The front face of the gear case 4 is brought into engagement with the rear face of the plate 6 with the boss 9 projecting into the slot 8 and the tubular stem 5 extending through the opening as a' in the rail a .

A vertically slotted plate 10 is then placed over and upon the front end of the threaded stem 5 and against the front face of the rail a and is held in place by a nut 11 which engages the threaded stem 5 and also serves to clamp the plate 6 against the rear face of the rail a and the gear case 4 against the rear face of the plate.

The front plate 10 is provided with a vertically elongated slot $10'$ for receiving the threaded stem 5 and permitting a limited adjustment of said plate ver-

tically to conform to rails of different widths, said plate —10— being provided with a shoulder —12— below the threaded stem —5— for engaging the underside of the rail —a— and thereby cooperating with the stem —5— in holding the plate against lateral displacement.

A rock shaft —13— is journaled in the tubular member —5— and extends beyond the opposite ends thereof, the rear end being operatively connected by a train of gears, presently described, to the armature shaft —2— of the motor while the front end extends beyond the corresponding end of the threaded sleeve or bushing —5— for receiving a U-shaped hub —14— of an oscillating arm —15—.

The hub —14— is splined on the rock shaft —13— and is held in fixed relation thereto by a set screw —16— carrying one end of the oscillating arm —15—.

The lower end of the plate —10— is provided with a forwardly projecting stud —17— parallel with and some distance below the rock shaft —13— and upon which is journaled one end of a wiper supporting arm —18— carrying a flexible wiper —19— which bears directly against the front face of the wind shield glass as —A'—, Figure 4.

The wiper supporting arm —18— is movable in a plane about the axis of the stud —17— between the plane of movement of the arm —15— and front face of the glass —A'— and is adapted to be oscillated about said axis through the medium of suitable connections with the arm —15— and for this purpose the wiper supporting arm —18— is provided intermediate its ends with a boss —21— having an aperture —22— through which the arm —15— extends so that any oscillatory motion imparted to the arm —15— will be transmitted to the wiper supporting arm —18—.

The object of pivoting the wiper supporting arm —18— to the plate —10— below the lower edge of the rail —a— is to allow said arm to swing through an arc of substantially 180 degrees or from a position against the underside of the rail at one side of the pivot —17— to a position against the rail at the opposite side of said pivot thereby permitting the wiper to travel over a greater area of the glass then would be possible if the wiper were secured directly to the arm —15— or radial to the rock shaft —13— in all positions of movement.

Gear train.

The portion of the armature shaft —2— extending into the gear case —4— is provided with a gear worm —23— meshing with a worm gear —24— which is mounted upon an upright tubular shaft —25— car-

rying a pinion —26—, the lower end of the shaft —25— being journaled in a suitable bearing —27— on the bottom of the case —4— while its upper end may be journaled in a similar bearing —29— on the top of the case.

The pinion —26— meshes with a relatively larger gear —30— having an upright supporting shaft —31— which is journaled in a bearing —32— on the bottom of the gear case —4—, said bearings —27— and —32— being closed at the bottom to permit the retention of oil in the case for lubricating the several gears and to lubricate the several rotating parts therein.

A gear segment —33— is pivotally journaled at —34— in a suitable bearing —35— in the bottom of the gear case to swing horizontally in a plane between the gears —24— and —30—, said gear being extended forwardly from its pivot —34— and provided at its forward end with a toothed segment —36— in mesh with a pinion —37— on the inner end of the rock shaft —13—, said pinion being located within the gear case —4— and against the inner end of the tubular bushing —5—.

The inner end of the bushing —5— is tapered and tightly fitted in a correspondingly tapered socket —38— in the front end of the gear case —4— to hold said bushing in fixed relation to the gear case and to permit said gear case to be easily and quickly removed or replaced from or upon the rail —a— of the wind shield by simply removing or replacing the nut —11—.

The opposite ends of the bearing —3— for the motor shaft —2— are also tapered and tightly fitted in correspondingly tapered sockets —39— and —40— in the opposite end walls of the gear case —4— as shown more clearly in Figure 2, the side of the bearing —3— adjacent the worm gear —24— being cut away at —31— to permit the meshing of the worm and gear and also to permit lubrication of the intermeshing teeth of those parts by the oil within the gear case.

A link —41— is pivoted at one end —42— to the gear —30— at one side of its axis and has its other end pivoted at —43— to the gear segment —33— near the front end thereof for imparting reciprocal motion thereto and, through the medium of the pinion —37—, causing the shaft —13— with the arm —15— thereon to oscillate the wiper supporting arm —18— through an arc of substantially 180 degrees as previously explained.

The gear case —4— is preferably divided horizontally at —44— in a plane above the gear —24— to form a removable top section —4'— which is normally secured to the lower section by screw bolts —45— so that

it may be removed when necessary for inspection or repairs of the parts within the gear case, the lower section being adapted to receive and retain a quantity of oil for lubricating those parts and the bearings therefor.

The entire motor —1— including the armature and field magnets are supported wholly outside of the gear case —4— at one end 10 thereof, the armature being supported wholly by the shaft —2— and bearings —3— while the field magnet as —46— is secured by bolts —47— to the adjacent end of the gear case.

The outer end of the armature shaft is 15 provided with a commutator —48— engaged by suitable brushes —49—, Figure 6, said brushes being yieldingly held against opposite sides of the commutator by supporting arms —50—, said arms being mounted upon 20 supporting posts —51— on the field magnet —46— at one side of the armature of the motor and are connected by a spring —52— for yieldingly holding the brushes —49— in contact with the commutator.

25 The entire motor including the field magnet —46—, commutator —48— and brush holders —50— are inclosed in a suitable housing —53— having one end telescopically fitted upon the adjacent end of the gear case 30 —4— and secured thereto by screws —54— or equivalent fastening means whereby the motor housing may be removed when desired, the outer end of said housing being provided with a journal opening —55— in 35 which is journaled the intermediate portion of a switch lever —56— having one end extending to the outside of the adjacent end of the housing to form a handle by which it may be turned and its other end provided 40 with an offset —57— at the inside of the housing for engaging one of the brush holders —50— whereby when the lever is rocked in one direction, the corresponding brush will be moved out of engagement with 45 the commutator to break the motor circuit and thereby stop the operation of the motor when desired.

The switch lever —56— is held in its adjusted position by washers —58— and —59— 50 engaging respectively the outer and inner faces of the adjacent end wall of the housing —53— and connected to each other through an axial opening in the lever by means of a screw or a rivet —60—, Figure 55 2, the disk —59— being concavo-convex in cross section and preferably made of spring metal so that when tensioned by the tightening of the screw —60— it will frictionally hold the lever —56— in its adjusted position.

The lever —56— is provided with a lateral offset —61— near its axis engaging in a slot —62— in the disk —58— to cause the disk to rotate therewith, the offset end as 60 —57— being engaged in a similar radial

slot 63 in the periphery of the inner disk —59— to cause the latter to rotate with the lever.

The periphery of the disk —59— is provided with circumferentially spaced shoulders —64— for engaging a stop pin —65— on the adjacent end wall of the cover —53— for limiting the movement of the lever —56— and thereby limiting the opening movement of the brush holder actuated 75 thereby as may be required for opening and closing the motor circuit as —C—, Figure 6.

During the operation of the gear train in the gear case —4— the oil will be splashed about more or less therein and will be transferred to the gears and bearings therefor and to a suitable disk —67— and wick —68— of felt or other absorbent material which will retain more or less of the lubricant for further distribution to the gears and bearings in case the oil supply in the reservoir of the gear case is lowered.

Operation.

Assuming that the switch member —56— is adjusted to close the motor circuit thereby transmitting rotary motion to the shaft —2— and worm gear —24— and through the pinion —26— to the gear —30— which through the medium of the pitman link 95 —41— will impart an oscillatory motion to the gear segment —33— for rocking the shaft —13— first in one direction and then in the opposite direction.

This rocking motion will be transmitted 100 to the arm —15— which in turn will impart similar rocking motion to the wiper supporting arm —18— and its wiper —19— across the surface of the glass —A— but about a different axis as that of the stud 105 —17— some distance below the shaft —13— and rail —a—, the ratio of gears of the gear train being arranged to cause the wiper —18— to move through an arc of substantially 110 180 degrees and this oscillating movement will be maintained as long as the motor is in operation or until the switch lever —56— is adjusted to break the motor circuit by simply moving one of the brush 115 holders and its brush out of contact with the commutator.

The particular arrangement of the gear transmission between the continuously rotating shaft —2— and rock shaft —13— not only operates the wiper arm with considerable force by the expenditure of a very small amount of current but also renders this operation practically noiseless and allows parts of the gear train to be assembled within an extremely small gear case mainly 125 within the height of the wind shield rail —a— to which it is attached and furthermore, by using the plates —6— and —10— against the inner and outer faces of the rail —a— in the particular relation described 130

enables the entire gear case and motor case with the various operating parts therein to be fastened in place by a single nut as —11—, all of which greatly reduces the cost 5 of manufacture and installation.

What I claim is:

1. In a motor driven windshield cleaner, a flanged plate adapted to be applied to the face of the windshield frame with its flange 10 engaging one of the edges thereof to hold it against turning relatively to the frame, said plate having a vertical slot therein, a gear case having a post adapted to extend through the said slot and through an opening in the frame when the cleaner is adjusted for use, means on the front end of the post for engaging the adjacent face of the frame to hold the gear case in engagement with said plate, said gear case having a boss at one 20 side of the axis of the post engaging in the slot of the plate for holding the gear case against turning movement relatively to said plate, a rock shaft extending through the post, a wiper arm actuated by the rock shaft 25 and means for oscillating the rock shaft.

2. In a mounting for windshield cleaners, a plate, means for securing the plate to the front face of the top rail of a windshield frame, said plate having a vertically elongated slot and a rearwardly projecting shoulder engaging the underside of said rail to hold it against lateral turning movement, a wiper pivotally mounted upon the lower end of the plate below said shoulder for a lateral swinging movement across the face of the windshield, a rock shaft adapted to extend through an opening in said rail and through the slot in said plate some distance above the wiper pivot, means actuated by the rock shaft for transmitting oscillatory motion to the wiper, and means for rotating the rock shaft in reverse directions.

3. In a mounting for windshield cleaners, plates adapted to engage respectively the rear and front faces of the top rail of a windshield frame, the rear plate having its upper edge provided with a forwardly projecting

flange for engaging the upper edge of the rail, the front plate being provided with a rearwardly projecting shoulder for engaging the lower edge of the rail, said plates being provided with vertically elongated slots, a motor support applied to the rear face of the rear plate and provided with a tubular post adapted to extend through the slots in both plates and through an opening in said rail, means engaging the front end of the post for clamping the support and plates to the rail, a boss on said support projecting into the slot of the rear plate, a rock shaft journaled in the post, a motor on the support for rocking the shaft in reverse directions, a wiper pivoted to the front plate to swing about an axis parallel with and some distance below the rock shaft, and means for transmitting motion from the rock shaft to the wiper.

4. In a mounting for windshield cleaners, the combination with a motor supporting frame having a tubular post adapted to extend through an opening in the windshield frame, of a clamping plate having a vertical slot for receiving said post and a shoulder for engaging the underside of the windshield frame, said post having means for pivotally supporting a windshield wiper, and means including a motor driven shaft extending through the tubular post for oscillating the windshield wiper.

5. In a mounting for windshield cleaners, the combination with a motor supporting frame having a tapered opening in one side, a tubular post having a tapered head engaged with the walls of said opening and adapted to be mounted in an opening in the windshield frame, shaft extending through said post and actuated by said motor, and means for drawing the post endwise in the direction of its taper and for simultaneously clamping the motor supporting frame to a windshield frame.

In witness whereof I have hereunto set my hand this 13th day of May, 1925.

ALBERT E. DOMAN.
